BUCKLE.

Application filed May 25, 1926. Serial No. 111,500.

The present invention relates to what is termed novelty jewelry and particularly to a buckle or clasp having a removable symbol or initial member.

5 Heretofore many different kinds of jewelry embodying removable initial members or stones have been used, particularly in connection with finger rings.

The application of a removable initial member to a buckle as provided by the present invention, however, necessitated a novel rearrangement of the component parts of the buckle in order to provide a simple structure and at the same time maintain the required 10 durability and assurance of locking the initial in place to avoid accidental loss.

A buckle is used under conditions that are different from those under which a finger ring is used. The latter is usually given a certain amount of care in handling, whereas, a buckle as when used on a shoe is frequently subjected to impacts and jars. When, therefore, an initial member is to be incorporated in a buckle it must not only be 20 constructed for expeditious and convenient attachment or removal, but must include fastening means of such a character as to avoid the possibility of dislodgment from careless use.

30 An object of the present invention, therefore, is to provide a simple and attractive ornament having a removable portion which may be replaced by another portion in a convenient and expeditious manner.

35 Another object of the invention is to provide a rigid mounting constructed and arranged to embody means for securing the mounting to an article.

40 Other objects and advantages will be apparent as the description proceeds.

A buckle constructed in accordance with the present invention may comprise a frame to receive an initial. The initial may be mounted on or may be part of a removable plate which may be secured to the frame. The several parts are so arranged that the initial member can quickly be replaced by another member without the exercise of skill and with a minimum amount of effort.

45 A storekeeper need therefore, only stock the usual number of buckles with sets of different initials or symbols and may readily

meet a demand for a set of buckles with a given initial or symbol.

The invention will be more fully understood by reference to the accompanying drawings in which:

Fig. 1 is a top view of a buckle embodying my invention;

Fig. 2 is an enlarged back view of the buckle shown in Fig. 1 partly broken away;

Fig. 3 is a sectional view of the buckle taken on line III—III in Fig. 2 but showing the initial member in position before being locked;

Fig. 4 is a sectional view taken on line III—III in Fig. 2 showing the initial member locked in position;

Fig. 5 is a sectional view taken on line V—V in Fig. 2; and

Fig. 6 is a view of a flexible backing member or insert which serves as a flap to sew or otherwise attach the mount to an article.

As an example of one embodiment of the invention I have illustrated its application 75 to a buckle for use on a shoe or slipper in which case I provide a frame 5 slightly bowed to conform with the shape of the article to which it may be applied.

The frame is preferably made of metal 80 as silver, or brass-silver plated and the exposed surface or face 6 may be left plain or ornamented by engraving or embossing to give an attractive appearance to the article.

85 The frame 5 is adapted to receive a removable initial member in the form of a plate 7 the ends of which are seated in extensions or on lips 8 and 9 at opposite edges of the inner side of the frame (see Fig. 2).

The plate 7 may also be slightly bowed but its normal curvature is of a less radius than that of the frame. When the plate is disposed on the lips 8 and 9, therefore, it extends slightly above the face of the frame 95 as shown in Fig. 3. The plate is, however, made of a flexible material as a metal and when locked in position is flexed to take the curve of the frame and lie flush with the said face thereof. The purpose of this construction will presently be described.

100 The plate may be adorned with any pleasing design and may have an initial or other symbol integral with or attached to its ex-

posed surface. The frame 5 is provided with a cross-piece 11 which is preferably made integral with the frame as are the lips 8 and 9 all being formed from a single sheet 5 of metal and the complete structure for carrying the plate 7 may be termed a mounting or mount. The lips are sufficiently offset from the face of the frame 5 to allow for the thickness of the plate 7 to permit it to 10 be properly noted with its exposed surface flush with the face of the frame or mount. Means for removably attaching or locking the plate to the mount may comprise a pivoted part 12 comprising a flat member 13 15 having arcuate edges 14 and 15 adapted to be moved across apertures 16 and 17 in the cross-piece 11. The pivoted part or locking member 12 may be provided with a tubular stud 18 pressed from the flat member 13. 20 The stud may extend through a suitable hole in the cross-piece 11 and may be riveted to hold the locking member 12 in position for oscillatory movement.

A slot 19 may be provided in the member 25 13 for the reception of a tool as a screw driver to actuate the member. Association between the locking member and the plate 7 is attained through a pair of stems 21 and 22 which extend from the concave side of 30 the plate 7 and when the same is in position for attachment to the mount, the stems enter and project through the apertures 16 and 17. The exposed ends of the stems are provided with notches 23 and 24 so that 35 when the member 13 is moved the arcuate edges 14 and 15 thereof engage with the stems and hold the plate in proper relation to the frame 5. In applying the plate 7 for attachment to the mount it is pressed tightly 40 against the lips 8 and 9 until it takes the general curvature of the frame and when in such position it is slightly flattened and attains an internal tension. When the plate is thus flexed and pressed against the lips 45 of the mount the notches 23 and 24 of the stems are in position to be engaged by the locking member 12 and when engaged therewith the plate is held under tension and any play or lost motion is avoided. The resilient retention of the initial member is important in an article of the present character. 50

When the buckle is used on a lady's shoe, for example, any vibration or impact during use in the case of loose parts, would result 55 in undesirable sounds or wear and perhaps the loss of the initial member. The present invention, although providing a removable initial member which may be readily supplied by a storekeeper, is of such construction that the initial member may be locked and the several parts constitute a composite article having the solidity of a single piece member.

In combination with the locking means the 60 present invention provides an insert or back-

ing piece 25 of a flexible material as leather or cloth for attaching the buckle to a shoe, as by sewing. This backing is also employed as a filling to give a pleasing contrast to the buckle by showing through any 70 openings as 26 which may occur in the design.

The mount is so constructed as to secure the insert or backing piece thereto. For this purpose the cross-piece 11 is offset from 75 the concave face of the frame to embrace the backing piece which is disposed between the plate 7 and the cross-piece 11. The backing piece is provided with a central aperture 27 to permit stems 21 and 22 of the 80 plate to pass through the cross-piece 11 and is also provided with collateral indentations 28 and 29 to permit the backing piece to substantially cover the whole area of the mount and show through any openings that 85 may be part of the design.

The locking means which may comprise the cross-piece 11 and the locking member 12, therefor, not only locks the plate to the 90 mount, but in conjunction with the insert 95 25, provides means for securing the buckle to the article upon which the buckle is to be used.

Although an article of the type above set forth is generally termed a buckle it is in 95 the true sense an ornament and it is to be understood that many uses may be made thereof and modifications made therein without departing from the spirit and scope 100 of the invention as set forth in the appended claims.

What is claimed is:

1. An ornamental device comprising a frame, a resilient member, a stem projecting from said member and means for engaging said stem when said member has been flexed to conform to the shape of said frame. 105

2. An ornamental device comprising a frame, an initial member, a stem extending from said member, a cross-piece on said frame having an aperture to receive said stem and a locking member engageable with said stem to secure said plate in contact with said frame. 110

3. An ornament comprising a mount including a frame, an initial member in the form of a resilient plate, a stem extending from said plate, a cross-piece on said frame having an aperture to receive said stem, and a locking member to engage an end of said stem when said plate is pressed in tensional engagement with said frame. 115

4. A buckle comprising a frame of bowed shape, an initial plate bowed with a normal radius of curvature less than that of the frame, a crosspiece on said frame having an aperture, a stem extending from said plate and through said aperture, and means for holding said plate in contact with said frame. 120 125 130

5. A buckle comprising a frame, a resilient initial member, lips adjacent the inner edges of said frame to seat said member, a cross-piece on said frame having apertures, 5 stems on said member arranged to enter said apertures, a backing piece between said member and said crosspiece and means for securing said member to said cross-piece.
6. A buckle comprising a frame, a pair of 10 oppositely disposed lips on the inner edges of said frame, an initial member disposed within said frame and seated on said lips, a pair of stems projecting from said member, a flexible insert for attaching the buckle to 15 another article, a cross-piece on said frame for embracing said insert, said cross-piece having apertures to receive said stems, said insert having an aperture to permit the 20 passage of said stems through said cross-piece and means for locking said stems to

the cross-piece to hold the initial member on said frame and for securing said insert to said buckle.

7. A buckle comprising a frame, an initial member, extensions upon the inner edge of 25 said frame to seat said initial member, a stem projecting from said initial member, an insert for attaching said buckle to another article, a cross-piece on said frame disposed to embrace said insert, said cross-piece having an aperture to receive said stem, said insert having an aperture to permit the passage of said stem through said cross-piece and means for locking said stem to the cross-piece to hold the initial member 30 in position and to secure the insert to said frame.

In testimony whereof I have affixed my signature.

LOUIS LEHR
